UNITED STATES PATENT OFFICE.

JOSEPH C. CRAMER, OF ROSEBURG, OREGON.

INSUFFLATOR.

1,122,257.

Specification of Letters Patent. Patented Dec. 29, 1914.

Application filed June 24, 1914. Serial No. 847,101.

To all whom it may concern:

Be it known that I, JOSEPH C. CRAMER, a citizen of the United States, residing at Roseburg, in the county of Douglas and 5 State of Oregon, have invented a new and useful Insufflator, of which the following is a specification.

The present invention appertains to insufflators or inhalers, and aims to provide a 10 novel and improved device of that character.

The present invention contemplates the provision of an insufflator adapted to be readily carried in the pocket, and which is of unique construction whereby it may be 15 readily employed for snuffing or drawing a charge of disinfectant germicide powder, or the like, into the nasal passage or respiratory tract for destroying or preventing propagation of micro-organisms, or conta-

20 gious disease germs.

As a more specific object, the present invention aims to provide an insufflator having a main or storage compartment or chamber adapted to contain a supply of disinfectant germicide powder or the like, in combination with a secondary or auxiliary chamber or cavity having a restricted inlet communicating with the main chamber, whereby when the insufflator is properly 25 manipulated, a charge of the powder may be permitted to flow into the secondary or auxiliary chamber from which it may be readily inhaled or drawn into the nostril.

It is also within the scope of the invention, to provide an insufflator of comparatively simple, compact and inexpensive construction, having means for effectively closing the same when not in use, to prevent the powder becoming damp, leaking out, or becoming contaminated with dust or other foreign matter, and the device being simple, convenient, practical, serviceable and efficient in its use.

With the foregoing and other objects in view which will appear as the description proceeds, the invention resides in the combination and arrangement of parts and in the details of construction hereinafter described and claimed, it being understood 50 that changes in the precise embodiment of the invention herein disclosed, can be made within the scope of what is claimed, without departing from the spirit of the invention.

The invention has been illustrated in its

preferred embodiment in the accompanying drawing, wherein:—

Figure 1 is a perspective view of the insufflator as in use. Fig. 2 is an enlarged side elevation of the device, and Fig. 3 is 60 a longitudinal section thereof.

The present insufflator includes a barrel or receptacle 1 of any suitable size and material, and which provides a main or storage chamber or compartment for holding the 65 disinfectant germicide powder, or the like. The barrel 1 is intended to hold one or more drams of powder, which will be sufficient for the use of the insufflator for a considerable period of time. The mouth portion of 70 the barrel 1 is reduced in diameter as at 2, and a ring 3 is secured upon the barrel adjacent the reduced end portion or neck 2, in order to facilitate the handling of the barrel 1.

A cap 4 of metal or other material has its open end slipped over the reduced end or neck 2 of the barrel 1, and its other end is rounded to form a dilating tip, and is provided with a central outlet aperture or 80 orifice 10. The rim or periphery of the cap 4 has a bayonet slot 5 at the open end of the cap, and which is engageable with a lug 6 provided upon one side of the neck 2 to enable the cap 4 to be readily applied to and 85 removed from the barrel neck, for the purpose of refilling the barrel or cleaning the corresponding parts.

A fiber or other disk or partition 7 is secured within the cap 4 intermediate its ends, 90 and is provided with a central restricted aperture or opening 8. The disk or partition 7 forms with the tip portion of the cap, a secondary or auxiliary chamber or cavity 9 adapted to hold a charge of the powder 95 consisting of a few grains thereof. The cap 4 is provided with an aperture or vent 11 at one side and providing an air inlet communicating with the chamber or cavity 9 adjacent the disk or partition 7. When the 100 cap 4 is applied to the neck 2 of the barrel 1, it is seatable against the shoulder formed by the neck, and the disk or partition 7 will be disposed adjacent the neck of the barrel, whereby the aperture 8 will provide a restricted passage between the main powder chamber or compartment and the auxiliary chamber or cavity 9.

In order to normally close the apertures 10 and 11, to prevent moisture, dust, or other 110

foreign matter from entering the barrel, and to prevent the powder from leaking out, an outer cap or closure 12 of metal or other material is slipped over the cap 4. When the 5 cap 12 is slipped over the cap or dilating head 4 having the auxiliary chamber 9, it will surround and inclose the cap 4 to close the apertures or vents 11 and 10.

In use, when the cap 4 is removed, the 10 barrel 1 may be readily filled with the disinfectant germicide powder, or the like, and may contain one or more drams of the powder to furnish a considerable number of charges. Then, when the caps 4 and 12 are 15 applied, the barrel 1 will be tightly closed, as is desirable, and the device may be readily carried in the pocket. Then, when the device is to be used as a curative or preventive for micro-organisms, or contagious disease 20 germs, the cap 12 is drawn or slipped off of the dilating head or cap 4, and the forefinger is placed over the aperture 10 to close the same, in which event, the barrel is tilted or turned upside down, which will cause a 25 charge of the powder to trickle or flow through the aperture 8 into the auxiliary chamber or cavity 9. The barrel 1 is then manipulated by the hand, as seen in Fig. 1, to apply the dilating head or cap 4 to the 30 nostril, whereby the outlet aperture 10 will communicate with the nasal passage. Then, the operator in inhaling or sniffing through the corresponding nostril, will cause a current of air to be drawn into the chamber 9 through the aperture or vent 11, and thence through the outlet aperture 10 into the nasal passage or respiratory tract. The 35 air being drawn into the chamber 9, will agitate the charge of powder therein, whereby the powder will be drawn into the nostril and distributed along the walls of the nasal 40 passage or respiratory tract, destroying or preventing the propagation of micro-organisms or contagious disease germs. It is of course to be understood that the insufflator 45 can be applied to both nostrils. After the device has been used, the cap 12 may be re-applied, to close the apertures 10 and 11,

so that the device may again be carried in the pocket, or the like.

The amount of powder contained in the charge admitted into the chamber 9, when the device is inverted, depends upon the size of the aperture 8, as will be apparent, it being obvious that the disk or partition 7 may 55 be replaced by others having different sized apertures 8, as may be desired. Each charge of powder only contains but a few grains of powder, so that the powder contained in the main or storage chamber will last for 60 a considerable period of time, it only being necessary to employ the device occasionally.

The device may be constructed in various sizes and proportions, and of various materials, as may be desired or demanded by the 65 user.

Having thus described the invention, what is claimed as new is:—

1. An insufflator including a barrel, a cap engaged over the mouth thereof, the cap 70 having an apertured dilating tip, and an apertured partition therein forming an auxiliary chamber communicating with the chamber of the barrel, and the cap having an aperture at one side providing an air 75 inlet communicating with the auxiliary chamber.

2. An insufflator including a barrel, a cap engaged over the mouth thereof, the cap having an apertured dilating tip, an apertured partition therein forming an auxiliary chamber communicating with the chamber of the barrel, the cap having an aperture at one side providing an air inlet communicating with the auxiliary chamber, and an 80 outer cap adapted to be slipped over the said cap to close the aperture and air inlet of the 85 cap.

In testimony that I claim the foregoing as my own, I have hereto affixed my signature 90 in the presence of two witnesses.

JOSEPH C. CRAMER.
